(57) **CLAIM**

I claim the ornamental design for display panel with a transitional computer-generated icon, as show and described.

DESCRIPTION

FIG. 1 is a front view of display panel with a transitional computer-generated icon showing the first image in the sequence for a transitional image;

FIG. 2 is a front view of display panel with a transitional computer-generated icon showing the second image in the sequence for a transitional image;

FIG. 3 is a front view of display panel with a transitional computer-generated icon showing the third image in the sequence for a transitional image;

FIG. 4 is a front view of display panel with a transitional computer-generated icon showing the fourth image in the sequence for a transitional image;

FIG. 5 is a front view of display panel with a transitional computer-generated icon showing the fifth image in the sequence for a transitional image;

FIG. 6 is a front view of display panel with a transitional computer-generated icon showing the sixth image in the sequence for a transitional image;

FIG. 7 is a front view of display panel with a transitional computer-generated icon showing the seventh image in the sequence for a transitional image;

FIG. 8 is a front view of display panel with a transitional computer-generated icon showing the eighth image in the sequence for a transitional image;

FIG. 9 is a front view of display panel with a transitional computer-generated icon showing the ninth image in the sequence for a transitional image;

FIG. 10 is a front view of display panel with a transitional computer-generated icon showing the tenth image in the sequence for a transitional image; and,

FIG. 11 is a front view of display panel with a transitional computer-generated icon showing the eleventh image in the sequence for a transitional image.

The broken line showing of the portion of the display panel is included for the purpose of illustrating environmental structure and forms no part of the claimed design.
